(No Model.)

J. J. PEETZ.

RAILROAD SWITCH.

No. 378,213.

Patented Feb. 21, 1888.

UNITED STATES PATENT OFFICE.

JOHN J. PEETZ, OF GALVESTON, TEXAS, ASSIGNOR TO HIMSELF AND
EDWARD J. BIERING, OF SAME PLACE.

RAILROAD-SWITCH.

SPECIFICATION forming part of Letters Patent No. 378,213, dated February 21, 1888.

Application filed March 18, 1887. Serial No. 231,403. (No model.)

To all whom it may concern:

Be it known that I, JOHN J. PEETZ, of Galveston, in the county of Galveston and State of Texas, have invented a new and Improved 5 Railroad-Switch, of which the following is a full, clear, and exact description.

My invention relates to railroad-switches, and has for its object to provide a simple, inexpensive, efficient, and safe switch adapted 10 for operation by trip-bars on a locomotive engine or car to open or close the switch, and without injury to the rails or actuating mechanism of the switch or danger of derailing the cars.

15 The invention consists in a certain novel feature of construction and combinations of parts of the railroad-switch, all as hereinafter fully described and claimed.

Reference is to be had to the accompanying 20 drawings, forming a part of this specification, in which similar letters of reference indicate corresponding parts in all the figures.

Figure 1 is a plan view of my improved railroad-switch. Fig. 2 is a transverse sectional elevation taken on the line $x-x$, Fig. 1. 25 Fig. 3 is a transverse sectional elevation taken on the line $y-y$, Fig. 1, with an end or front view of the engine-pilot, and illustrates how the switch is operated therefrom; and Fig. 4 30 is a detail side view of the pilot, showing one arrangement of tripping devices thereon for operating the switch.

The main-line rails A B of the track are cut away to give room for the switch-rails C C, 35 which are pivoted at $c-c$ at one end, and at or near their other ends are connected at $d-d$ to a cross-bar, D, fitted to slide transversely of the track. A lever, E, which is pivoted about at its center at e to a support on the road-bed, is 40 provided with an arm, F, having a slot, f, through which a pin, d' , on the cross-bar D passes, and the opposite ends of this lever are connected pivotally by links G H with latch-bars I J, which are connected pivotally at one 45 end with the opposite switch-rails, C C, and are adapted by their other ends, i j, to lock against stop-lugs K L, fixed to one of the ties or a timber on the road-bed, for holding the switch open or closed, as presently explained. 50 Rails A' B' form with the switch-rails C C,

when the latter are adjusted as shown in Fig. 1 of the drawings, the turnout or siding track.

To the lever E there are pivoted at $m-n$, respectively, at opposite sides of the lever-fulcrum e, a couple of rods, M N, which are connected pivotally at $m'-n'$ to a curved lever, O, at opposite sides of its pivot or fulcrum o, and the opposite ends, o' o'', of the lever O are adapted to be struck by trip-bars on the engine-pilot, when the train is moving in the direction of the arrow 1 in Fig. 1, for setting the switch, as hereinafter described. Long rods S T, which are pivoted at $m-n$, respectively, to the lever E, are pivoted at $s-t$ at their other ends to trip levers or plates U V, adapted, respectively, for operation by trip-bars carried by engine-pilots of trains moving on the main-line rails A B toward the switch in direction of the arrow 2 in Fig. 1, and on the side-track rails A' B', moving toward the switch 60 rails in the direction of the arrow 3 in the drawings.

The trip-bars W X are fitted for vertical movement at opposite sides of the engine-pilot, (shown in part at Y in Figs. 3 and 4 of the drawings.) Each of these trip-bars slides through bearings at $w-w$ on brackets w', held to the pilot floor or frame, and a spring, w^2 , acting between the lower bearing and a collar on each trip-bar normally forces the bar up clear of the 75 lever O, U, or V, and in which position it will not act to shift the switch. The trip-bars W X may be lowered to strike the levers O, U, or V either by means of a treadle-lever, Z, connected to a rock-lever, z, pivoted to the 80 bearing w and connected to the trip-bar, or by means of a piston working in a cylinder, Z', to which steam will be admitted by the engineer. Crossed bars or rods w^3 may be used to brace the lower ends of the trip-bar bearings to the floor or frame of the engine-pilot. 85

The operation of the switch is as follows: We will suppose a train is approaching the switch on the main line in direction of the arrow 1 in Fig. 1 of the drawings, and the switch 90 connects the main-line with the siding rails A' B', the switch-rails C C then being locked in position by the engagement of the end i of the latch-bar I with the lug K. Should the engineer wish to run his train onto the siding, 95

he will leave both the trip-bars W X raised, so as not to operate the lever O; but should he wish to keep the main line he will lower the right-hand trip-bar W, which will strike the end o' of the lever O and throw it forward, thereby rocking the lever E, and the first effect will be to draw the latch-bar I from the stud K, the slot f in the arm F allowing this without causing movement of the switch-rail bar D, and the continued movement of the lever E after the end of the slot f strikes the pin d' will shift the bar D endwise and swing the rails C C into line with the rails A B, and as the switch-rails take these positions the end j of the latch-bar J will lock behind the stud L to hold the switch-rails in place for a continuous main-line track. If the switch is in line with the main rails and a train approaching in direction of the arrow 1 is to take the siding, the engineer will lower the left-hand trip-bar X, which will strike the end o' of lever O, and first unlock the bar J from the stud L, and then throw the switch-rails open and lock them for the siding by the bar I, or as shown in Fig. 1 of the drawings. As a train approaches the switch on the main line from the opposite direction, or that of the arrow 2 in Fig. 1, the engineer may always lower the left-hand trip-bar, X, to strike the lever U for assuring the alignment of the switch-rails to the main line, and should the switch be already so positioned the lowered trip-bar would simply pass by the lever U without operating it. Should a train be approaching the main line from the side track, A' B', in direction of the arrow 3 in Fig. 1, the engineer will lower the trip-bar X, which will strike the lever V and set the switch-rails C C over to the siding-rails to allow the train to pass safely onto the main-line tracks A B. The levers O U V will be set a sufficient distance from the switch-rails to give ample time for the rails to be thrown and locked before the wheels of the engine strike them, as will readily be understood.

The trip-bar device may be adjusted to the cars of a train for operating the switch, as well as on the engine-pilot—as, for instance, the lever Z or an equivalent treadle or lever; or may be fitted on freight-cars, allowing a train-man on the car to set the trip-bar and shift the switch-rails for opening the main line to a side track when cars are to be run onto the main track from the side track.

Having thus fully described my invention, what I claim as new, and desire to secure by Letters Patent, is—

1. The combination, in a railroad-switch and with the main-line rails A B and siding-rails A' B', of pivoted switch-rails C C, a bar, D,

connecting them, a lever, E, fulcrumed to the road-bed and having an arm, F, slotted at f, a pin, d', passed through said slot into the bar D, latch-bars I J, pivoted to the switch-rails, links G H, connecting the bars I J with the lever E, and lugs L K on the road-bed, against which the bars I J are adapted to lock to hold the switch open and closed, substantially as shown and described.

2. The combination, in a railroad-switch and with the main-line rails A B and siding-rails A' B', of pivoted switch-rails C C, a bar, D, connecting them, a lever, E, fulcrumed to the road-bed and having an arm, F, slotted at f, a pin, g', passed through said slot into the bar D, latch-bars I J, pivoted to the switch-rails, links G H, connecting the bars I J with the lever E, lugs K L on the road-bed, against which the bars I J are adapted to lock, a lever, O, fulcrumed to the road-bed, and rods M N, connecting the levers E O, substantially as shown and described.

3. The combination, in a railroad-switch, of main-line rails A B, siding-rails A' B', pivoted switch-rails C C, a bar, D, connecting the switch-rails, a lever, E, fulcrumed on the road-bed and having an arm, F, slotted at f, a pin, d', passed through said slot into the bar D, latch-bars I J, pivoted to the switch-rails, links G H, connecting the bars I J with the lever E, lugs K L on the road-bed, against which the bars I J may lock, a lever, U, fulcrumed to the road-bed, and a rod, S, connecting the levers E U, substantially as shown and described.

4. The combination, in a railroad-switch and with the main-line rails A B and siding-rails A' B', of pivoted switch-rails C C, a bar, D, connecting them, a lever, E, fulcrumed to the road-bed and having an arm, F, slotted at f, a pin, d', passed through said slot into the bar D, latch-bars I J, pivoted to the switch-rails, links G H, connecting the bars I J with the lever E, lugs K L on the roadside, against which the bars I J may lock, a lever, V, fulcrumed to the road-bed at the siding-rails, and a rod, T, connecting the levers E V, substantially as shown and described.

5. A trip-bar device carried by an engine or car for operating a railroad-switch, and comprising a bar, as X, fitted on the engine or car, a spring, w', adapted to normally lift the bar, and a cylinder, Z', containing a piston, connected to the bar X, substantially as shown and described.
